United States Patent Office

Des. 202,202
Patented Sept. 7, 1965

202,202

EXERCISER OR THE LIKE

Fred M. Gore, Dallas, Tex., assignor to Jules A. Green, Houston, Tex.

Filed Nov. 5, 1964, Ser. No. 82,484

Term of patent 14 years

(Cl. D34—5)

Fig. 2

The bottom is plain.

I claim:

The ornamental design for an exerciser or the like, substantially as shown and described.
